UNITED STATES PATENT OFFICE.

HARRY E. HEATH, OF WINDSOR, CONNECTICUT, ASSIGNOR TO THE EDDY ELECTRIC MANUFACTURING COMPANY, OF SAME PLACE.

DESIGN FOR A SHELL FOR ELECTRIC MOTORS.

SPECIFICATION forming part of Design No. 27,433, dated July 27, 1897.

Application filed June 15, 1897. Serial No. 640,923. Term of patent 7 years.

To all whom it may concern:

Be it known that I, HARRY E. HEATH, a citizen of the United States, residing at Windsor, in the county of Hartford and State of Connecticut, have invented and produced a new and original Design for Shells for Motor-Carriage Electric Motors, of which the following is a specification.

The object of the invention is the production of a design for the shells of electric motors built with special reference for use on motor-carriages which shall be artistically attractive to electricians and motor-carriage engineers and builders, as well as to others.

To produce an artistic effect, pleasing to those skilled in the art to which the invention is applied as well as to motor-carriage users and casual observers, the motor must have the appearance of being and must be light in weight, must have the appearance of being and must be powerful, and must have the appearance of being and must be compact.

On the accompanying sheet of drawings, which form a part of this specification, there is shown a motor-shell embodying a design having these characteristics, and of these—

Figure 1 shows an edge view; Fig. 2, an end view; Fig. 3, a plan view; Fig. 4, a section on *a a*, and Fig. 5 a section on *b b*, all of these views being deemed necessary to a complete comprehension of the design.

As shown in the drawings, the leading or

material feature of the design resides in the rectangular shape of the pole-frame 1 and the tapering shapes of the caps 2 and 3, that are connected with the pole-frame and with it form the shell of the motor.

The pole-frame, as shown in Figs. 2 and 5, is a single rectangular oblong wrought-iron band or hoop. Extending from one side of this rectangular oblong frame is a cap 2, which is a single aluminium piece that tapers quickly from a rectangular oblong shape in cross-section at the frame to a circular shape in cross-section at the outer end, as shown in Fig. 3. Extending from the other side of the frame is the aluminium cap 3. This latter cap is in two parts, one of which tapers more gradually than the taper of the cap 2 from a rectangular oblong shape in cross-section at the frame to a semicircular shape at the outer end, as shown in Figs. 2 and 3, while the other part of this cap is substantially semicircular—that is, is a short section of a hollow semi-cylinder. A line is visible where the tapering part of this cap and the semicircular part of the cap join.

I claim as my invention—

The design for a shell for motor-carriage electric motors, herein shown and described.

HARRY E. HEATH.
